Primary Examiner — Philip S Hyder(74) *Attorney, Agent, or Firm* — Reinhart Boerner Van Deuren s.c.(57) **CLAIM**

I claim the ornamental design for a cutting tool, as shown and described.

DESCRIPTION

FIG. 1 is a rear perspective view from above of an embodiment of the claimed design;

FIG. 2 is a front perspective view from below of the claimed design of FIG. 1;

FIG. 3 is a top view of the claimed design of FIG. 1;

FIG. 4 is a bottom view of the claimed design of FIG. 1;

FIG. 5 is a right view of the claimed design of FIG. 1;

FIG. 6 is a left view of the claimed design of FIG. 1;

FIG. 7 is a rear view of the claimed design of FIG. 1; and,

FIG. 8 is a front view of the claimed design of FIG. 1.

1 Claim, 6 Drawing Sheets(56)
